AUTOMOBILE GRILLE

John E. Schwarz, Oak Park, Mich., assignor to Chrysler Corporation, Highland Park, Mich., a corporation of Delaware

Filed May 23, 1960, Ser. No. 60,683

Term of patent 7 years

(Cl. D14—18)

Fig. 1 is a front view of an automobile grille embodying my new design;

Fig. 2 is a top plan view thereof;

Fig. 3 is an end elevational view thereof;

Fig. 4 is a sectional view taken on the line 4—4 of Fig. 1; and

Fig. 5 is an elevational view taken on the line 5—5 of Fig. 2.

The dominant features of my design reside in the portions shown by means of full lines in the drawing.

I claim:

The ornamental design for an automobile grille, substantially as shown and described.
